(57) **CLAIM**

The ornamental design for a wall hanger hook, as shown and described.

DESCRIPTION

FIG. 1 is a front perspective view of the wall hanger hook.
FIG. 2 is a front view of the wall hanger hook.
FIG. 3 is a back view of the wall hanger hook.
FIG. 4 is a right side view of the wall hanger hook.
FIG. 5 is a left side view of the wall hanger hook.
FIG. 6 is a top view of the wall hanger hook.
FIG. 7 is a bottom view of the wall hanger hook; and,
FIG. 8 is a back perspective view of the wall hanger hook.
The broken (dot-dash) lines illustrate perimeters of unclaimed surface areas and form no part of the claimed design.

1 Claim, 6 Drawing Sheets
